PYROPHORIC LIGHTER

Hans Silberknopf, Vienna, Austria

Application October 21, 1936, Serial No. 106,743
In Austria November 25, 1935

5 Claims. (Cl. 67—7.1)

This invention relates to improvements in ignition devices and has particular reference to a pyrophoric lighter.

Heretofore a type of lighter has been used wherein a fuel-containing casing is slidably mounted in a sleeve member and connected to a wick cap in such manner that when pressure is applied to the casing in one direction to move the same relative to the sleeve member, such movement will, through said connection, adjust the wick cap to an open or uncovering position so that the wick may be lighted. There is further provided a spring means operable to automatically restore the casing and wick cap to their normal positions when the casing, which must be held in its operated position against the tension of said spring means, is released.

In the proper manipulation of the above-described lighter, the outer sleeve member is gripped in the fingers of one hand with the index finger embracing said sleeve member at the top thereof adjacent the wick cap, and with the friction wheel of the igniting means disposed on the inner side of the lighter nearest the thumb so that said wheel may be conveniently engaged by the thumb preparatory to exerting a downward pressure upon the casing which carries said wheel. The sleeve member is of such length that the first three fingers of the hand will engage therewith, but the little finger will be free, that is, disposed beyond the lower end of the sleeve member and casing before the latter is depressed. Then, when the casing is projected downwardly by the aforementioned pressure upon the friction wheel to move the wick cap to open position, at which time the wheel is rotated by the thumb to ignite the wick, the little finger is gripped around the projected portion of the casing so as to prevent its return to normal under the influence of said spring as long as it is desired to keep the wick uncovered. With the lighter thus in operation, the sleeve member and casing must be firmly held in the fingers without any shifting of the lighter in the hand since any release of the grip of the little finger upon the casing will permit of an inadvertent restoration of the casing and cap to normal, with a consequent extinguishment of the flame. Due to this inability to shift the lighter in the hand during the period of ignition of the wick, the index finger is in close proximity to the flame and unless care is exercised the finger will be burned; also, the handling of the lighter is considerably restricted and it cannot be passed from one person to another without the closing of the wick cap.

The present invention is designed for the purpose of overcoming the above difficulties by providing an improved latching means which will be effective, during use of the lighter, in preventing restoration of the wick cap to normal position under the influence of the spring means previously mentioned, thus avoiding the necessity of maintaining a continuous grip upon the casing and enabling the lighter to be shifted in the hand or passed to another person.

The inventive idea involved is capable of receiving a variety of mechanical expressions one of which, for purposes of illustration, is shown in the accompanying drawing wherein:

Figure 1 is a side elevation of the lighter constructed in accordance with the invention and with the parts in normal position.

Figure 2 is a view similar to Figure 1 but taken at right angles thereto.

Figure 3 is an elevation, partly in section, showing the parts of the lighter in operated position, and

Figure 4 is a section taken substantially on the line 4—4 of Figure 3.

As illustrated, the lighter comprises the cylindrical fuel-containing casing 5 provided at its lower end with a closure 6 for an opening in the casing through which fuel is injected, and at its upper end with a wick tube 7 having a wick 8 mounted therein. Secured along the casing and extending beyond its upper end is the usual holder 9 for the pyrophoric element 10 which is adapted to be engaged by the friction wheel 11 rotatably supported in a bracket 12 at the upper end of said holder, the element 10 and wheel 11 being so situated with respect to the wick 8 that when said wheel is briskly rotated the sparks from the pyrophoric element will impinge upon the wick and ignite the same.

The casing 5 is slidably mounted in an open-ended cylindrical sleeve member 13 and, in the normal position of the casing, the same is enclosed within said sleeve member with the exception of the upper end of the casing. However, when the casing 5 is moved downwardly and longitudinally of the sleeve member by the exertion of pressure upon the friction wheel carried by the casing the lower end of the latter is projected from the sleeve member to the position shown in Figure 3, in which position the wick 8 is recessed within the upper end of the sleeve member which then acts as a windguard for the wick after it has been ignited by a turning movement of the friction wheel.

A wick cap 14 has its opposed arms 15 pivotally connected at diametrically opposite points, as at

16, to the upper end of the sleeve member 13 and in the normal position of said wick cap the same covers the wick 8 and fits upon its tube 7 so as to effectively seal the wick therein. When the casing 5 is forced downwardly preparatory to igniting the wick, means are provided for moving the cap 14 about its pivot to an uncovered position relative to the wick. This means is in the form of a yoke 17 pivoted to the arms 15 and extending laterally therefrom. Joined to the intermediate portion of the yoke 17, as by an eye 18, is one end of a connecting element 19 the other end of which is secured to an intermediate portion of the casing 5 by means of a curved plate 20 extending circumferentially of the casing so as to straddle the element 19 and riveted or otherwise suitably secured to the casing and to the connecting element. The element 19 is preferably in the form of a flat rod made of spring metal, and said rod and yoke 17 are so proportioned that when the parts are in the normal position of Figure 1, the upper end of the connecting rod is sprung outwardly. The upper portion of the element 19 is normally disposed between the edges of a cutout portion 21 formed in the upper end of the sleeve member 13. When so disposed, the intermediate portion of the plate 20 which straddles the element 19 projects into the slot 21 and is guided by engagement with the edges of said slot when the casing is moved relative to the sleeve member, and vice versa, and also by reason of such engagement said intermediate portion assists in preventing any rotary movements of the casing and sleeve member with respect to each other. From the lower end of the cutout portion 21 to the bottom of the sleeve member the latter is formed with an outstruck portion 22 which provides a groove open at its upper end to receive the element 19 and closed at its lower end by an inturned portion 23 constituting an abutment the purposes of which will presently appear. In the side wall of the casing 5 the same is instruck to form a groove 24 which extends from the bottom of the casing to a point intermediate the ends thereof and with the parts assembled said groove 24 is in opposed relation to the groove formed by the outstruck portion 22, thereby combining therewith to form a channel. The groove 24 receives the abutment 23 and the engagement of the latter with the walls of said groove also assists, together with the intermediate portion of the plate 20, in preventing any rotary movement between the casing and sleeve member. In said channel there is introduced a coil spring 25 the lower end of which engages the abutment 23 while the upper end contacts the adjacent end of the groove 24 and also the lower end of the element 19 and its holding plate 20. The spring 25 is expanded in the normal position of the lighter but when the casing 5 is moved downwardly to the position of Figure 3, said spring is compressed so as to exert an upward pressure upon the casing and element 19 while the sleeve member is being held in the hand which pressure is sufficient to automatically restore said parts to their normal positions and thus move the wick cap 14 into covered relation to the wick 8 unless the casing is gripped in its projected position by the little finger of the hand.

70 Means are further provided for releasably retaining the casing and wick cap in their operated positions after the wick 8 has been lighted so that an inadvertent restoration of the casing and wick cap to normal positions under the influence of the spring 25 will be prevented. Said means

5 is in the form of a latching device consisting of a detent 26 formed on the connecting element 19 adjacent its upper end and adapted, when the parts are in operated position, to engage in an opening 27 formed in the sleeve 13 adjacent its upper end. This engagement or latching position is effected in the following manner. When the casing is forced downwardly by the pressure of the thumb against the friction wheel 11 the projecting or upper portion of the connecting element 19 starts to move into the groove formed by the outstruck portion 22 and the upper end of the latter engages the outwardly flexed portion of said element 19 so as to bend the same inwardly and thus place the element under tension. Upon reaching the extreme of its downward movement the detent 26 registers with the opening 27 and due to the tension under which said element has been placed the detent projects outwardly into said opening and thus engages the upper edge of the opening to latch the casing, sleeve member and wick cap in their operated positions. When it is desired to restore the parts to normal positions after the lighter has been used, the latter is held between the thumb and one finger with one of the digits engaged with the holder or tube 9 and the other with the eye 18. Then by exerting a squeezing pressure, the element 19 will be flexed inwardly to disengage the detent 26 from the opening 27, whereupon the spring 25 will become effective to force the sleeve member 13, which is no longer gripped in the hand, downwardly relative to the casing 5. This movement of the sleeve member results in the connecting element 19 exerting an upward pressure upon the yoke 17 so that the latter, together with the wick cap 14, will swing about their respective pivots to position the wick cap in alignment with the tube 7 and thus receive the wick 8 therein as the sleeve member approaches 20 and reaches its normal position.

25 What is claimed is:

1. A pyrophoric lighter, an open-ended cylindrical sleeve member having an outwardly offset portion forming a longitudinal groove and said portion having an opening therein, a cylindrical fuel-containing casing slidable within said sleeve member and having an instruck portion constituting a groove opposed to the groove in said sleeve member and combining therewith to form 30 a channel having abutments at the ends thereof, a wick carried by said casing, igniting means for said wick, a cap for said wick pivoted to said sleeve member, a flexible connecting rod joining said cap and casing and movable in the groove 35 of said sleeve member, said rod having a detent engageable in the opening in said offset portion when the casing has been moved to a position in which said cap has uncovered the wick, and a spring in said channel compressed by the relative movement of said casing in one direction so as to become effective to move said sleeve member in the same direction to thereby restore said cap to covering position when said detent is disengaged from said opening.

2. In a pyrophoric lighter, an outer sleeve member and a fuel-containing casing having relative sliding movements, a wick for said casing, igniting means for said wick, a cap for said wick pivoted to said sleeve member, a resilient rod secured at one end to said casing and connected at its other end to said cap for adjusting the latter to covering and uncovering positions with respect to said wick when relative movements occur between said casing and sleeve member, means 40

5 acting upon said connection and sleeve member to urge said cap toward its covering position, and a detent formed on said rod for engagement with a portion of said sleeve member to releasably retain said cap in uncovering position and said casing in the position wherein its wick is exposed to said igniting means.

3. In a pyrophoric lighter, an outer sleeve member having an offset portion and a slot aligned therewith, said offset portion having an opening therein, an inner casing having sliding movements in said sleeve member, cooperating igniting means carried by said casing and including a wick, a cap for said wick, a resilient rod movable in said slot and having one end secured to said casing for movement therewith into said offset portion, the other end of said rod being connected to said cap, a detent on said rod engaged, by the resiliency of the latter, in the opening in said offset portion to latch said cap in an open position relative to said wick when said casing is moved in said sleeve member, and a spring in said offset portion for restoring said cap to covering position relative to said wick when 10 said detent is disengaged from said opening by pressure upon said rod.

4. In a pyrophoric lighter, an outer sleeve member having an offset portion and a slot aligned therewith, said offset portion having an opening therein, an inner casing having sliding movements in said sleeve member, cooperating igniting means carried by said casing and including a wick, a cap for said wick, a resilient rod disposed in said slot and having one end secured to said casing for movement therewith into 15 said offset portion, the other end of said rod being

connected to said cap, a plate for securing the first named end of said rod to said casing and having a portion projecting into said slot and engageable with said offset portion during movements of said casing to retain the latter against rotary movement relative to said sleeve member, a detent on said rod engaged by the resiliency of the latter in the opening in said offset portion to latch said cap in an opened position relative to said wick when said casing is moved in said sleeve member, and a spring in said offset portion for restoring said cap to covering position relative to said wick when said detent is disengaged from 20 said opening by pressure upon said rod.

5. In a pyrophoric lighter, an outer sleeve member having an offset portion and a slot aligned therewith, said offset portion having an opening therein, an inner casing having sliding movements in said sleeve member, cooperating igniting means carried by said casing and including a wick, a cap for said wick, a yoke carried by said cap, a resilient rod disposed in said slot, means to secure one end of said rod to said casing, the other end of said rod being normally bowed outwardly from said casing and terminating in an eye for receiving said yoke, a detent on said rod adjacent said eye and guided into said opening by engagement of said rod with said offset portion when the casing is moved in said sleeve member, said eye forming a means to 25 thereafter flex said rod to disengage said detent from said opening, and a spring in said offset portion acting upon said rod to restore said cap to its covering position relative to the wick after disengagement of said detent. 30
